COOL SMOKE PIPE

Edward A. Germain, New York, N. Y.

Application September 28, 1939, Serial No. 296,870

7 Claims. (Cl. 131—198)

This invention relates to new and useful improvements in a cool smoke pipe, cigarette holder or the like.

More specifically the invention proposes the construction of a mouth piece for a pipe, cigarette holder or the like which has a main longitudinally extending smoke passage in a manner to permit smoke to be drawn from the burning tobacco contained within the pipe bowl or cigarette.

Still further it is proposed that a plurality of branch transverse passages be connected with said longitudinally extending smoke passages in a manner to permit cool air to be drawn into the passages to be mixed with the smoke in a manner to cool the same.

Still further it is proposed to locate the branch transverse passages at such a position in said mouth piece that they may be controlled by the engagement of the lip thereover while the mouth piece is in one's mouth for controlling the entrance of the air therethrough.

Still further it is proposed to provide a mechanical means in the form of a slide movably mounted in said mouth piece and adapted to be normally shifted in a manner to close said transverse passages when desired.

Still further it is proposed to provide a plurality of auxiliary slides on said slide being individually adjustable for selectively controlling the passage of air through said transverse passage.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a pipe having a mouth piece constructed in accordance with this invention.

Fig. 2 is a plan view looking in the direction of the line 2—2 of Fig. 1.

Fig. 3 is a sectional view taken on the line 3—3 of Fig. 2.

Fig. 4 is a view similar to Fig. 2 but illustrating a modification of the invention.

Fig. 5 is a sectional view taken on the line 5—5 of Fig. 4.

Fig. 6 is another view similar to Fig. 2 but illustrating still another modification of the invention.

Fig. 7 is an enlarged sectional view on the line 7—7 of Fig. 7.

Fig. 8 is an enlarged sectional view on the line 8—8 of Fig. 6.

The cool smoke pipe, cigarette holder, or the like, according to the invention includes a mouth piece 10 for connecting with a pipe, cigarette holder, or the like. In the drawing the mouth piece 10 is shown associated with a pipe having a bowl portion 11 into which tobacco is adapted to be placed. A main longitudinally extending smoke passage 12 extends through the mouth piece 10 and connects with the bowl portion 11 for permitting the smoke to be drawn therethrough from the burning tobacco into one's mouth.

A plurality of branch transverse passages 13 extend from the smoke passage 12 to the top face of the mouth piece 10. These transverse passages permit air to be sucked into the passage 12 to be mixed with the smoke coming from the burning tobacco for cooling the same before it enters one's mouth. These transverse passages 13 are so positioned along the length of the mouth piece 10 that one's upper lip may be used to control the entrance of air therethrough. The lip may be engaged against the open edge of the passages 13 for preventing the entrance of air or may be removed therefrom to permit free entrance of air.

The operation of this form of the invention is as follows:

Tobacco is placed within the bowl 11 of the pipe and the same is lit and the mouth piece 10 is engaged into one's mouth for conveying the smoke from the bowl to one's mouth. If desired the transverse passages 13 may be left uncovered for permitting outside air to pass into the smoke passage 12 and mix with the smoke coming from the burning tobacco for the purpose of cooling the same. If too much air is entering the transverse passages 13 and it materially thins the smoke coming from the burning tobacco, several or all of the transverse passages may be closed by engaging one's lip thereover for preventing air passing therethrough into the smoke passage.

According to the modification of the invention shown in Figs. 4 and 5 the construction of the mouth piece is similar to that previously described except for the provision of a mechanical means for controlling the passage of air through the transverse passage 13. In this form of the invention the mouth piece 10' is formed of separate sections consisting of a main portion 10a and a top portion 10b. The top portion 10b is formed on the side of the smoke passage 12 which

has the transverse passage 13 and the passages extend therethrough.

The adjacent faces of the portions 10a and 10b are provided with a cut out area in which a slide 14 is mounted. This slide is provided with a plurality of openings 15 spaced from each other a distance similar to the spaces between the transverse passages 13.

The sides of the slide 14 are formed with outwardly extending lugs 14a which extend to the sides of the mouth piece 10 for permitting the slide to be moved to position in which the passages 13 and the openings 15 will be aligned or in a position in which the passages 13 and the openings 15 will be disaligned. It is also possible to move the slide 14 into a position in which the openings 15 will be partially aligned with the passages 13 for permitting the limited entrance of air through the passages to mix with the smoke 20 coming from the burning tobacco for the purpose of cooling the same.

In other respects this form of the invention is identical to the prior form and the same parts may be recognized by the same reference numerals.

According to the modification shown in Figs. 6, 7 and 8, the construction of the mouth piece 10" is similar to that previously described except for the provision of the slide 16 for simultaneously closing all of the transverse passages 13 and an individual slide 17 for each of the transverse passages 13 for the purpose of individually closing the same as desired. In this form of the invention the mouth piece 10" is also formed of a main portion 10a and a top portion 10b similar to that shown in Figs. 4 and 5. The slide 16 is longitudinally movable and is provided with a plurality of openings which are adapted to align with the passages 13. The openings 18 are spaced from each other the distance similar to the distance at which the transverse passages 13 are spaced from each other.

The auxiliary slides are slidably mounted in recesses 16a formed in the top face of the slide 16. These slides 17 extend beyond the sides of the mouth piece 10 and are adapted to be used for shifting the slide 16 longitudinally of the mouth piece for aligning or disaligning the openings 18 and the passages 13. Each of the slides 17 is formed with an opening 19 which is adapted to be aligned with its respective opening 18 in the slide 16 and its respective passage 13. These slides 17 are adapted to be shifted transversely of the mouth piece 10" and the slide 16. When the openings 18 and the passages 13 are in alignment the slide 17 may be individually shifted to align or disalign its respective opening 19 with its respective opening 18 and passage 13 for controlling passage of smoke through its respective passage 13.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A cool smoke pipe, cigarette holder, or the like, comprising a mouth piece for a pipe, cigarette holder or the like, having a main longitudinally extending smoke passage, and a plurality of branch transverse passages through

which air may be sucked to cool the smoke, and said transverse passages being controlled with one's lips, a slide movably mounted on said mouth piece and in one position being adapted to cut off said transverse passages, said slide being formed with a plurality of openings alignable with said transverse passages permitting a free passage of air therethrough, and a plurality of auxiliary slides on said slide for selectively controlling said transverse passages when said first mentioned slide is in a position in which its openings are aligned with said transverse passages.

2. A cool smoke pipe, cigarette holder, or the like, comprising a mouth piece for a pipe, cigarette holder or the like, having a main longitudinally extending smoke passage, and a plurality of branch transverse passages through which air may be sucked to cool the smoke, and said transverse passages being controlled with one's lips, a slide movably mounted on said mouth piece and in one position being adapted to cut off said transverse passages, said slide being formed with a plurality of openings alignable with said transverse passages permitting a free passage of air therethrough, and a plurality of auxiliary slides on said slide for selectively controlling said transverse passages when said first mentioned slide is in a position in which its openings are aligned with said transverse passages, said first mentioned slide being slidable longitudinally on said mouth piece and said auxiliary slides being slidable transversely of said mouth piece.

3. A cool smoke pipe, cigarette holder, or the like, comprising a mouth piece for a pipe, cigarette holder or the like, having a main longitudinally extending smoke passage, and a plurality of branch transverse passages through which air may be sucked to cool the smoke, and said transverse passages being controlled with one's lips, a slide movably mounted on said mouth piece and in one position being adapted to cut off said transverse passages, said slide being formed with a plurality of openings alignable with said transverse passages permitting a free passage of air therethrough, and a plurality of auxiliary slides on said slide for selectively controlling said transverse passages when said first mentioned slide is in a position in which its openings are aligned with said transverse passages, said auxiliary slides being mounted in grooves formed in the top face of said first-mentioned slide for permitting said auxiliary slides to be used for shifting the position of said first-mentioned slide.

4. In a device of the class described, a mouth piece having a main longitudinally extending smoke passage, a plurality of transverse passages extending upwards from said smoke passage through which air may be sucked to enter said smoke passage and mix with the smoke passing therethrough to cool the same, a slide longitudinally slidably mounted in said mouth piece and movable for simultaneously opening and closing all of said transverse passages, and a plurality of auxiliary slides transversely slidably mounted in said mouth piece for selectively closing certain of said transverse passages in the open position of said first-mentioned slide.

5. In a device of the class described, a mouth piece having a main longitudinally extending smoke passage, a plurality of transverse passages extending upwards from said smoke passage through which air may be sucked to enter said smoke passage and mix with the smoke passing therethrough to cool the same, a slide longitudinally slidably mounted in said mouth piece

and movable for simultaneously opening and closing all of said transverse passages, and a plurality of auxiliary slides transversely slidably mounted in said mouth piece for selectively closing certain of said transverse passages in the open position of said first-mentioned slide, said auxiliary slides being mounted within a groove formed in the top face of said first-mentioned slide so that the ends of said auxiliary slides may be used 10 for moving said first-mentioned slide longitudinally of said mouth piece.

6. In a device of the class described, a mouth piece having a main longitudinally extending smoke passage, a plurality of transverse passages 15 extending upwards from said smoke passage through which air may be sucked to enter said smoke passage and mix with the smoke passing therethrough to cool the same, a slide longitudinally slidably mounted in said mouth piece and 20 movable for simultaneously opening and closing all of said transverse passages, and a plurality of auxiliary slides transversely slidably mounted

in said mouth piece for selectively closing certain of said transverse passages in the open position of said first-mentioned slide, said slides being located in said mouth piece intermediate the ends of said transverse passages.

7. In a device of the class described, a mouth piece having a main longitudinally extending smoke passage, a plurality of transverse passages extending upwards from said smoke passage through which air may be sucked to enter said 10 smoke passage and mix with the smoke passing therethrough to cool the same, a slide longitudinally slidably mounted in said mouth piece and movable for simultaneously opening and closing all of said transverse passages, and a 15 plurality of auxiliary slides transversely slidably mounted in said mouth piece for selectively closing certain of said transverse passages in the open position of said first-mentioned slide, said slides having openings alignable with said transverse 20 passages in the open position of the slides.

EDWARD A. GERMAIN.
